Primary Examiner — Vy N Koenig*Assistant Examiner* — Michelle M Reeves(74) *Attorney, Agent, or Firm* — Morgan, Lewis & Bockius LLP(57) **CLAIM**

The ornamental design for a hair accessory organizer, as shown and described.

DESCRIPTION

FIG. 1 is a front perspective view of a hair accessory organizer showing my new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines illustrate features of the hair accessory organizer that form no part of the claimed design.
